[57] CLAIM

The ornamental design for a sanitizing station for hands, as shown.

DESCRIPTION

FIG. 1 is a perspective view taken from the top, front and right side of a sanitizing station for hands showing my new design;

FIG. 2 is a perspective view taken from the bottom, rear and right side thereof;

FIG. 3 is a top plan view thereof;

FIG. 4 is a front elevational view thereof;

FIG. 5 is a right side elevational view thereof, the left side being a mirror image of the right side;

FIG. 6 is a bottom plan view thereof;

FIG. 7 is a rear elevational view thereof;

FIG. 8 is a perspective view taken from the top, front and right side of a second embodiment thereof;

FIG. 9 is a perspective view taken from the bottom, rear and right side of FIG. 8;

FIG. 10 is a top plan view of FIG. 8;

FIG. 11 is a front elevational view of FIG. 8;

FIG. 12 is a right side elevational view of FIG. 8, the left side being a mirror image of the right side;

FIG. 13 is a bottom plan view of FIG. 8; and,

FIG. 14 is a rear elevational view of FIG. 8.
